CLAIM

The ornamental design for a machine to spray chemicals, as described and shown.

DESCRIPTION

FIG. 1 is a perspective environmental view of a machine to spray chemicals of the present invention.

FIG. 2 is a front perspective view of the machine to spray chemicals of FIG. 1.

FIG. 3 is a rear perspective view of the machine to spray chemicals of FIG. 1.

FIG. 4 is a left side perspective view of the machine to spray chemicals of FIG. 1.

FIG. 5 is a right side perspective view of the machine to spray chemicals of FIG. 1.

FIG. 6 is a top plan perspective view of the machine to spray chemicals of FIG. 1; and,

FIG. 7 is a bottom plan perspective view of the machine to spray chemicals of FIG. 1.

The broken line showing is for illustrative purposes only and forms no part of the claimed design.
